United States Patent Office.

JACOB H. SHEAR, OF ALBANY, NEW YORK.

Letters Patent No. 94,658, dated September 7, 1869.

IMPROVEMENT IN COOKING-STOVES.

The Schedule referred to in these Letters Patent and making part of the same.

To whom it may concern:

Be it known that I, JACOB H. SHEAR, of the city and county of Albany, and State of New York, have invented a new and useful Improvement in Cooking-Stoves; and I hereby declare the following to be a full and exact description of said improvement, reference being had to the accompanying drawings, and to the letters of reference marked thereon, the same letter always referring to the same part of the stove.

The improvement has reference to such an organization and arrangement as will tend to modify the per cent. of combustion within the fire-pot, within any given time, to any desirable degree, and also to equalize the rate of combustion in every part of the fire-pot, and upon the grate, producing a uniform rate of combustion in or on every part of the grate.

My said improvement consists in so introducing the air for sustaining combustion into the fire-chamber as that the coal at the extremities of the grate shall burn equally well with that upon the centre of the grate. To do this, compensation must be made for the excess of radiation going on at the ends of the grate, for it is well known, in the practical operation of stoves, that the tendency is for the fire to die first at the end of the grate or fire-pot, where the radiation is the greatest.

This being the case, provision for such compensation must be made in well-organized stoves having an elongated grate or fire-pot.

Figure 1, in the accompanying drawings, is a representation of a stove having provision made therein for such compensation.

The door of the stove *a a*, in fig. 1, is a compound-chambered door, consisting of two chambers, front and rear, connected with each other by means of flues or openings in the upper sides of the partition, separating them, so located, in respect to each other; as that there is a closed space between them, as seen in Figure 4, *c c*.

The second chamber is formed by means of a plate, *d d*, Figure 5, so attached to the inside of the door as that the openings into the stove and under the grate shall be at the ends and on the lower side of such chamber, as seen in Figure 2, *d d*.

The manner in which the air enters these chambers is represented in fig. 1, at the openings *a' a'*.

It is to be observed that this compound-chambered door is so constructed that the air enters on the lower side and near the ends of the first or front chamber. Thence it arises to the top of the chamber, and enters the second chamber through the openings *c c* in fig. 4. It then descends to the bottom of the second or rear chamber, and enters the stove through the openings *d d* at the points *g g*, fig. 2, and thus

furnishes air in a proper condition and location to aid combustion in the ends of the grate.

These chambers are made to exclude the passage of air at or near the middle of the chamber, for the purpose of compelling all the air passing the chambers to pass to the ends of the grate and fire-pot, to produce increased combustion, there to compensate for the increased radiation in that part of the fire-pot.

To aid further in the matter of compensation, I introduce warm air within the fire-pot, near the ends of the same, by means of flues *b b*, as seen in figs. 1 and 2. Air is supplied to these flues *b b* through the openings at *k* in the top of the stove, fig. 1.

It must be observed that the air aiding combustion at the ends of the grate is so introduced for that purpose that it becomes more or less heated while in its passage to the grate by taking up caloric which is being radiated, and by these means it returns, for aid in the support of the moderate combustion desired in the fire-pot, caloric, which would otherwise pass off and be dissipated or lost for such purpose.

Connected with this improvement, and for united action with the same, are the dampers *e* and *f* in the exit-pipe, fig. 1.

I have demonstrated, by long-continued experiments, that the improvement is complete by means of using these dampers, and particularly by the use of the damper *f*.

The improvement can be worked very well by the use of the damper *f* only, although it is more perfect by the use of both *e* and *f*.

I have likewise demonstrated that the improvement is not complete without the united action of one or both these dampers.

When I wish to keep up a very moderate fire upon the entire length of the grate, for any considerable time, as from evening until morning, or from morning until morning again, without attending to the fire in the meantime, I see that the fuel on the grate is in well condition for ignition, and properly supplied. I then close my compound-chambered door *a a*, fig. 1, opening the lower draughts therein, *a' a'*.

I also open the draught-damper *e* and close the damper *f* in the exit-pipe.

By thus operating my stove, I find I can keep the coal upon the grate, from end to end, alive with fire from eighteen to twenty-seven hours without further attention, and consuming in the meantime only about twenty to twenty-five pounds of coal; but by neglecting the arrangement as above described, the fire uniformly goes out before morning.

I have repeated these experiments constantly for many weeks with uniform results, and have thus de-

demonstrated the actuality and value of my said improvements, and that the said chambers, flues, and dampers co-operate to produce the desired result.

I have also experimented, during the time above mentioned, for the purpose of testing the value of the improvement, which compels the air to pass into the fire-pot from the ends of the chambers in the door, instead of passing in through a continuous opening from the chamber, that is, an opening along the bottom, and from end to end of the chamber, and the result has been uniform that, when I compelled the air to enter the fire-pot from the lateral end flue only, the combustion on the ends of the grate has been kept up, but when I extended the flue-opening entirely across the chamber, the fire at the ends has died down; therefore, I adopted the division of the flue-openings in the chamber of my door as a part of

my said improvement; and when a chamber is located elsewhere than in the door, a like arrangement, with a view of affecting combustion in the ends of the grate, will also include this feature of my said improvement.

Having thus fully described my said invention and improvement,

I will now proceed to state what I claim, and desire to secure by Letters Patent.

In a cooking-stove, of the general construction and arrangement described, I claim the chambered door, grate, flues, dampers *e* and *f*, and exit-pipe, under the combination substantially as represented.

JACOB H. SHEAR.
